UNITED STATES PATENT OFFICE.

NORRIS ELMORE CLARK, OF PLAINVILLE, CONNECTICUT, ASSIGNOR TO THE NATIONAL METAL FABRIC COMPANY, OF NEW YORK, N. Y., A CORPORATION OF NEW YORK.

EXPANDED-METAL MANUFACTURE.

1,140,117.

Specification of Letters Patent.

Patented May 18, 1915.

Application filed August 25, 1906. Serial No. 331,981.

To all whom it may concern:

Be it known that I, NORRIS ELMORE CLARK, a citizen of the United States, residing at Plainville, Hartford county, Connecticut, have invented certain new and useful Improvements in Expanded-Metal Manufacture, of which the following is a full, clear, and exact description.

This invention relates to improvements in methods or processes of manufacturing expanded metal.

The right to claim the mechanisms herein disclosed is reserved for future applications.

The principal object of the invention is to provide a simple method of expanding sheet metal with rapidity and uniformity and at low cost.

Another and important object is to consecutively expand and wind or roll up the expanded product by the same instrumentality.

Another object is to slit and expand the metal by different instrumentalities.

Another object is to readily release the coil of expanded metal.

Different forms of mechanism are illustrated diagrammatically in the accompanying two sheets of drawings for carrying out my invention.

Figure 1 is a sectional view of a table and end view of two drums for carrying out one method of expansion. Fig. 2 is a similar view, but showing the drums diagrammatically only, for carrying the method into effect in slightly modified form. Fig. 3 is a similar view but showing a pair of rolls for retarding the metal. Fig. 4 is a similar view showing a plurality of friction retarding members. Fig. 5 is a side view of means for feeding, slitting and expanding consecutively. Fig. 6 is a plain view of the same, the slitting tools being, however, omitted. Fig. 7 is a diagrammatic side view of mechanism for slitting and then expanding according to the method of Fig. 1. Fig. 8 is a similar view for slitting and then expanding according to the method of Fig. 3.

Each of the expansive mechanisms illustrated is adapted to operate upon sheets or strips of stock which have been lanced or slit transversely of the direction of feed.

The slitting of the stock 1 may be effected by suitable punches, or other tools, 2-2, indicated diagrammatically in Fig. 5, or such as 2'-2' in Figs. 7 and 8, the feed of the

stock before slitting being controlled by rolls 3-3, and, if desired, the feed after slitting being controlled by rolls 4-4.

In order that the subsequent expanding operation may result in a more uniform product, it is sometimes desirable that the slit stock be rolled down flat and smooth by rolls such as 4-4. A table or other support, such as 5, may be used when the stock requires handling, from whence it is fed to the expanding mechanism.

The slit stock 6 in the method of operation shown in Fig. 1 is first wound on to a drum or cylinder such as 7, the front end of the slit stock being detachably secured to the drum by suitable means, for instance a key 8, the drum being turned in a direction opposite to the direction of the arrow.

The rear end of the stock is then brought forward and detachably secured to drum or cylinder 9, for instance by a suitable key 10. Drum 9 is then rotated in the direction of the arrow, and the drum 7 also rotated in the direction of its arrow but at a peripheral speed considerably less than the peripheral

speed of drum 9, the two drums for this purpose being preferably geared together, or driven from the same source, so that there shall be a positive difference in peripheral speeds. As a result, the strands of the slit stock 6 are separated from each other so as to form meshes, the degree or extent of expansion depending upon the difference in peripheral speeds of the drums. Practically the entire expansion takes place in that part of the metal which lies between the points of its tangency with the two drums.

In order that the expansion throughout the entire length of a strip (especially if the strip is of any considerable length) shall be uniform, the angular speed of the expansion drum 9 should gradually decrease as the winding and expansion takes place, and the angular speed of the retardation drum 7 gradually increase, so that the

actual linear speed of the outside layer on drum 9 shall remain constant, and the actual linear speed of the outside layer of the stock on drum 7 remain constant. For short strips, however, and a material not requiring great uniformity, such changes in angular velocity are not necessary.

When the expansion is complete, what is now the rear end of the slit stock is released from drum 7 and wrapped around 110

the coil on drum 9 and secured in place. Since the coiling of the expanded material upon drum 9 is accomplished under considerable pressure, either the coil should be loosened up in order to remove it from the drum, or the drum should be contracted. I prefer to accomplish the removal of the coil by contracting the drum, since this results in a more uniform and regular coil. For this purpose, the drum surface is preferably made up of a series of segments, as shown in Fig. 1, and each segment has a pin 11 projecting into a slot 12 in the ring 13. Rotation of the ring 13 draws all the segments toward the axis of the drum and thus reduces its diameter sufficiently to permit of the ready removal of the coil.

In the form of mechanism shown in Fig. 2, the stock is wound upon the retardation drum 7 in the direction the reverse of that in Fig. 1. The action of expansion is, however, substantially the same. The use of this mechanism, however, has the disadvantage of requiring a greater space between the points of tangency of the stock, or else a reduction in the diameter of the drums, which is not desirable.

In Fig. 3, the retardation of the stock is effected by engagement of the rolls 14-14, whose peripheral speed is less than the peripheral speed of expansion drum 9. With this form of mechanism to produce an absolutely uniform product it is simply necessary to decrease the angular velocity of drum 9 as the coil is wound up, or increase the angular velocity of the retardation rolls 14-14.

In Fig. 4, the drum 9 is driven as before, but the retardation is effected by means of friction entirely. Rolls 15-15 are provided simply for the purpose of steadyng the slit 40 | 45 | 50 | 55 | 60 | 65 | 70 | 75 | 80 | 85 | 90 | 95 | 100 | 105 | 110 | 115 | 120 | 125 |

In the mechanism of Figs. 5 and 6, retardation is effected by the rolls 3-3, while the expansion takes place intermittently by the action of the expansion drum after each stroke of the slitting tool. This requires but one handling of the stock.

In Fig. 7 is illustrated mechanism for feeding, slitting, rolling and expanding by separate operations such as would be used with the expansion and retardation mechanism of Figs. 1 and 2.

In Fig. 8, the slitting is accomplished as in Fig. 7, but intermediate handling is eliminated, the slit 70 | 75 | 80 | 85 | 90 | 95 | 100 | 105 | 110 | 115 | 120 | 125 |

The operation of my improved method of expansion produces material which is more or less flat, as set forth in my Patent No. 767,798, dated August 16, 1904. It is possible, however, by this method to produce more or less irregular stock by suitably increasing the rate of expansion or decreasing the diameter of the coiling drum. Lubrication of the slit 90 | 95 | 100 | 105 | 110 | 115 | 120 | 125 |

stock facilitates uniform expansion action. Omission of rolls such as 4-4 between the slitting and expansion operations also tends to result in the production of more or less irregular product. In each case, however, the material when expanded is all ready for shipment in compact form.

In speaking of transverse slitting it does

not mean that the slits must extend exactly at right angles to the line of feed but that the slitting is in such a direction and arrangement that the stock may be stretched or expanded forwardly substantially as herein set forth.

By "slitting" in its broad sense I mean any treatment of the metal

which outlines or defines a series of strands

connected at intervals whether the metal is punched out or entirely severed or not.

The use of a drum or similar device for drawing out the forward portion of the transversely slit 110 | 115 | 120 | 125 |

sheet avoids the use of expensive drawing rolls and also leaves the strands free to turn on edge since there is no pressure on the upper surface of the sheet. This coiling or winding action also provides a tension which is uniform across the entire sheet so that the stretching or expanding action is positively uniform.

What I claim is:

1. The improvement in the art of forming expanded metal which consists in retarding the feed of a transversely slit 125 | 130 |

part of the sheet is fed at a greater rate than the retarded portion of the sheet and the slitted sheet is opened into meshwork.

2. The improvement in the art of forming expanded metal which consists in retarding the feed of a transversely slitted sheet and in advance thereof applying a uniform positive tension across the entire sheet at one

face only of the sheet whereby the forward part of the sheet is fed at a greater rate ¹⁰ than the retarded portion of the sheet and the slitted sheet is opened into meshwork.

NORRIS ELMORE CLARK.
